Primary Examiner—Ted Shooman*Assistant Examiner*—Mitchell I. Siegel*Attorney, Agent, or Firm*—Richard B. O'Planick; Lisa B. Riedesel**[57] CLAIM**

The ornamental design for a seat panel for playground structure, as shown and described.

DESCRIPTION

FIG. 1 is a top left front perspective view of a seat panel for playground structure showing my new design;

FIG. 2 is a front elevational view thereof;

FIG. 3 is a left side elevational view thereof; the right side elevational view being a mirror image;

FIG. 4 is a top plan view thereof;

FIG. 5 is a bottom plan view thereof;

FIG. 6 is a rear elevational view thereof;

FIG. 7 is a top left perspective view thereof, shown without the environmental broken lines for clarity of illustration;

FIG. 8 is a front elevational view of FIG. 7; and,

FIG. 9 is a rear elevational view of FIG. 7.

The broken lines on FIGS. 1-6 are for illustrative purposes only and form no part of the claimed design.
